UNITED STATES PATENT OFFICE.

DAVID L. BARNES, OF CHICAGO, ILLINOIS, ASSIGNOR TO THE NATIONAL
MALLEABLE CASTINGS COMPANY, OF CLEVELAND, OHIO.

DESIGN FOR A CENTER PLATE FOR CARS.

SPECIFICATION forming part of Design No. 22,130, dated January 10, 1893.

Application filed November 2, 1892. Serial No. 450,685. Term of patent 14 years.

To all whom it may concern:

Be it known that I, DAVID L. BARNES, of Chicago, in the county of Cook and State of Illinois, have invented a new and original Design for Center Plates for Cars, of which the following is a full, clear, and exact description, reference being had to the accompanying drawing, which shows in perspective view a center plate embodying my design.

The design consists in a center-plate for car-bodies having the form and outline substantially as shown in the accompanying drawing and as herein described. As shown in

the drawing, the center-plate 3 has a vertical annular band 4, with ribs 5 which project radially from the said band. 15

I claim:—

The design for center-plates for cars substantially as herein shown and described.

In testimony whereof I have hereunto set my hand this 22d day of October, A. D. 1892.

DAVID L. BARNES.
